MATERIAL GATHERING AND LOADING
MACHINEJohn S. Housman, Chicago, Ill., assignor to
Goodman Manufacturing Company, Chi-
cago, Ill., a corporation of IllinoisApplication October 13, 1932, Serial No. 637,576
Renewed April 1, 1936

9 Claims. (Cl. 198—8)

This invention relates to improvements in material gathering and loading machines particularly adapted for operation in spaces of restricted vertical height for loading coal at the working face of a mine.

The principal object of the invention is to provide a mechanism of the character described particularly adapted for use in thin seams of coal for loading along a long face constructed with a view towards utmost compactness, simplicity, efficiency, maneuverability, and ease of operation.

Other objects of my invention will appear from time to time in the following specification:

My invention may be more clearly understood with reference to the accompanying drawings wherein:

Figure 1 is a top plan view of a loading machine illustrating one form in which my invention may be embodied, with parts broken away and in section to more clearly show the details thereof;

Figure 2 is a side elevation of the device shown in Figure 1;

Figure 3 is an enlarged side elevation of the forward portion of the device shown in Figure 1 with parts broken away and in section to more clearly show the details of my invention;

Figure 4 is an enlarged plan view of the rearward portion of the embodiment of my invention shown in Figure 1 with parts broken away and in section to more clearly show the details of my invention;

Figure 5 is a partial fragmentary longitudinal sectional view of the rearward portion of the device shown in Figure 1;

Figure 6 is a sectional view taken substantially along line 6—6 of Figure 3; and

Figure 7 is a working diagram of the device embodying my invention.

Like numerals refer to like parts throughout the various figures.

Referring now to the details of the machine as shown in Figures 1 and 2, the main elements thereof consist of a skid or main frame 10 having up-turned sides and ends and being adapted to rest on the mine bottom for slideable movement therewith, an inclined loading element 11 extending forwardly of said main frame and carried thereby, and a discharge conveyor 12 extending from beneath the rearward end of said loading element and thence upwardly and rearwardly in an extended overhanging position beyond the rearward end of said main frame so as to discharge material into suitable material conveying means.

The inclined loading element 11 includes a conveyor 14 supported in side frame members 15 on either side of the main frame 10 and extending forwardly therefrom, which side frame members, besides supporting the conveyor, form a means for retaining material thereon. The conveyor 14 is inclined for a portion of its length from a position disposed forwardly of the main frame 10 and its upper portion extends substantially horizontally rearwardly along said main frame to a point adjacent the rearward end thereof above the discharge conveyor 12.

The inclined conveyor 14 may be of any suitable construction which requires a minimum amount of vertical space, but is herein preferably shown as being made from a wire mesh belt 16 extending around a direction changing device 17 of a minimum diameter supported at its ends in the side frame members 15 adjacent the lower forward portion thereof and extending upwardly and rearwardly therefrom for a portion of its length along the upper side of a plate 18 and thence horizontally and rearwardly around a toothed drive roller 19. From the toothed drive roller 19, the wire mesh belt extends beneath the plate 18 along suitable guide means to the direction changing device 17.

The wire mesh belt 16 is of a usual construction made from interlaced strands of wire in a manner similar to woven wire fencing, and its particular advantages are that it forms a suitable efficient conveying medium for coal which may pass around direction changing devices of less diameter than other conveyor means and thus makes possible the construction of conveying mechanism of less vertical height than with other conveying mediums and keeps the height of the loading machine down to the minimum vertical requirements necessary for operation in thin seams of coal.

The forward ends of the side frame members 15 are inclined at an angle of incidence with respect to the ground upon which the machine rests greater than the conveyor 14 and form a means for supporting an inclined apron 21 which extends from a point adjacent the mine bottom and extreme forward lower ends of the side frame members 15 forwardly of the inclined conveyor 14 upwardly along the forward faces of said side frame members on each side of said inclined conveyor. A portion 22 of the inclined apron 21 extends rearwardly from the forward end thereof along the inner sides of the side frame members 15 in alignment with the lower portion of said side frame members to form in

effect a shoe for engaging an uneven mine bottom during the loading operation. The forward portion of the inclined apron 21 and lower portion of the forward ends of the side frame members 15 are concavely curved so as to form a curved support for chain guiding members 23. Said chain guiding members are so formed that their contour corresponds with the contour of the apron 21 and are disposed on each side of the conveyor 14. The chain guiding members 23 extend beyond the forward end of the conveyor 14 and forwardly of the forward end of the inclined apron 21.

Thus the chain guiding members 23 may guide suitable endless chains 24 for movement thereabout in a closed orbital path in such a manner that gathering means carried thereby may engage and move along the ground forwardly of said chain guiding members. The endless chains 24 are constructed in such a manner that they may readily follow the curved contour of the chain guiding members 23, which construction is well known to those skilled in the art so will not herein be shown or described in detail.

The gathering means carried by the endless chains 24 comprise a plurality of gathering arms 25 mounted thereon in a usual manner for engaging and moving the mined coal onto the conveyor 14.

An independent motor 27 is provided for driving each endless chain 24 so said endless chains may be operated independently with respect to each other in a simplified manner, thus eliminating complicated systems of gearing and clutches which necessarily add to the height and bulk of the machine.

Inasmuch as the drive from each motor to each endless chain 24 is similar, the drive from one motor only will herein be described.

The motor 27 is arranged so as to extend longitudinally of the main frame 10 and is substantially parallel to the inclined apron 21 and is supported on the outer side of the side frame member 15 beneath said inclined apron in a usual manner well known to those familiar with the art. A bevel armature pinion 28 is provided on the motor 27, which bevel pinion meshes with and drives a bevel gear 29 on a shaft 30 substantially perpendicular to the inclined apron 21. A pinion 31 is cut integral with the shaft 30 and meshes with and drives a spur gear 33 on a parallel shaft 34. A helical gear 35 is keyed on the shaft 34 adjacent the end opposite the spur gear 33 and meshes with and drives a helical gear 36 on a shaft 37 coaxial with the shaft 30. A sprocket 39 is keyed on the opposite end of the shaft 37 and meshes with the endless chain 24 for driving said endless chain.

It may thus be seen that a compact driving arrangement of minimum vertical dimensions has been provided for the endless chains 24, which driving arrangement is entirely beneath the inclined apron 21 and requires no vertical height additional to the height of the conveyor 14.

Referring now in particular to the means for feeding the inclined loading element 11 into the loose material and moving the main frame or skid 10 about the mine bottom, a plurality of feed drums 40 are provided on each side thereof. The feed drums 40 are coaxially arranged about a shaft 41 disposed transversely of the main frame 10 rearwardly of the discharge conveyor 12 and beneath the conveyor 14.

Each of the drums 40 is adapted to be independently driven from a motor 43, which motor is mounted on the main frame 10 adjacent the forward end thereof beneath the conveyor 14 and is provided with an armature shaft 44 extending longitudinally with respect thereto. A shaft 45 is coaxial with the armature shaft 44 and extends rearwardly therefrom and is journaled in suitable ball bearings in a suitable bearing support and worm and worm gear housing 46 and is operatively connected with the rearward end of the armature shaft 44 by means of a suitable flexible coupling generally indicated by reference character 47. A worm 48 is cut integral with the shaft 45 and meshes with and drives a worm gear 49 keyed on the transversely extending shaft 41 adjacent the central portion thereof for driving said shaft. The shaft 41 is journaled adjacent opposite sides of the worm gear 49 and is journaled in its ends within hubs 50 of casings 51 of planetary gear reduction devices generally indicated by reference character 52. The hubs 50 of the casings 51 are in turn journaled in suitable bearing supports generally indicated by reference character 53 secured to and extending upwardly from the main frame 10.

Inasmuch as each planetary gear reduction device 52 and the drive from said planetary gear reduction devices to the feed drums 40 is the same, the details of one only will herein be described. A sun gear 55 is keyed on the shaft 41 within the casing 51 and meshes with and drives planetary pinions 56, which planetary pinions in turn mesh with an internal gear 57 on the inner periphery of the casing 51.

The planetary pinions 56 are journaled on suitable stud shafts 59 having enlarged heads 60 abutting the outer side of the planetary pinions 56 and passing through a body portion 61 of the feed drum 40 and having a nut threaded on its opposite end abutting the outer side of said body portion for holding said stud shaft to said body portion. The body portion 61 of the feed drum 40 is in turn journaled on the shaft 41 by means of suitable ball bearings so said drum may rotate upon rotation of the planetary pinions 56 about the sun gear 55.

Suitable friction means are provided to engage the outer periphery of the casing 51 to hold said casing and the internal gear 57 from rotation or to permit slippage of said casing upon overload which may be of any type but which is herein preferably shown as being a friction band 63 which is engaged with or disengaged from the outer periphery of the casing 51 by means of a suitable system of levers in an ordinary manner (not shown).

It may thus be seen that when the internal gear 57 is held from rotation by means of the friction band 63, that the planetary pinions 56 will be driven about said internal gear by means of the sun gear 55 which in turn will drive the feed drum 40 through the stud shafts 59, that the speed of rotation of said drum may be varied by varying the pressure of the friction band 63 on the casing 51, and that, upon overload of said feed drum, the friction band 63 will slip on the outer periphery of the casing 51 which will prevent breakage of the parts in the drive for said feed drum.

It may further be seen that the friction band 63 serves as a clutch means for connecting the feed drum 40 to the shaft 45 in a simplified

manner so it may be driven therefrom and vice versa.

Suitable means are provided for braking the feed drums 40 and forming a means whereby either of said drums may serve as a retarding drum to retard movement of one portion of the machine while it is being moved by the opposite drum to aid in manipulating the machine about the mine, which means comprises friction bands 64 adapted to engage the outer periphery of flanges 65 integral with the outer sides of the feed drums 40 and extending over the casings 51 for a portion of their length so as to be disposed adjacent the friction bands 63 on the inner side thereof. The friction bands 64 may be engaged with or disengaged from the flanges 65 for holding the feed drums 40 from rotation or permitting said feed drums to be fed at a frictionally controlled speed by means of a suitable system of levers in a usual manner (not shown).

It may thus be seen that either of the feed drums 40 may be driven from the shaft 45 at a reduced frictionally controlled speed and that either of said drums may be held from rotation with respect to said shaft when disconnected therefrom to serve as a retarding device.

Suitable flexible feeding members 67 are adapted to be connected to and wound on the feed drums 40. The flexible feeding members 67 are adapted to extend forwardly from the feed drums 40 around guide sheaves 68 outwardly and forwardly therefrom around guide sheaves 69 disposed adjacent the forward outer ends of the main frame 10 for pulling the machine forwardly into the coal or along the face of the coal.

The flexible feeding members 67 may also extend around guide sheaves 70 in alignment with the guide sheaves 68 on the outer sides thereof and rearwardly therefrom around guide sheaves 71 to a guide sheave 73 disposed adjacent the longitudinal center line of the main frame 10 adjacent the rearward end thereof for moving the machine rearwardly along the mine bottom.

Referring now to the drive for the wire mesh belt 16 of the conveyor 14, a shaft 74 is coaxial with the shaft 45 and extends rearwardly therefrom. The shaft 74 is driven from the shaft 45 by means of a suitable flexible coupling generally indicated by reference character 75. A worm and worm gear drive, generally indicated by reference character 76, drives a transversely extending shaft 77 from the shaft 74. The outer end of the transversely extending shaft 77 is splined and engages the inner portion of a splined sleeve 78, which splined sleeve is journaled in suitable bearing supports extending upwardly from the main frame 10 and has a sprocket 79 freely mounted thereon. Suitable means are provided for operatively connecting the sprocket 79 with the splined sleeve 78 which may be of any construction but is herein preferably shown as being a jaw clutch of an ordinary type generally indicated by reference character 80. The sprocket 79 is in turn connected with the toothed drive roller 19 for driving said toothed drive roller by means of a suitable chain and sprocket drive generally indicated by reference character 81.

Thus the motor 43 serves as a means for independently driving both of the feed drums for moving the machine about the mine or feeding the inclined loading element 11 into the loose material and as a means for driving the conveyor 14, and said feed drums, motor, and drive

therefrom are of a simplified compact construction confined within the vertical limits of the inclined loading device 11, effecting an efficient drive for said feed drums and conveyor and maintaining a loading machine of a minimum 5 vertical height.

The discharge conveyor 12 includes a hopper 83 formed integral with the sides thereof beneath the discharge end of the conveyor 14, which hopper is mounted on a supporting member 85 adapted to be supported on the main frame 10 adjacent the rearward end thereof for rotation with respect thereto about a vertical axis.

The supporting member 85 includes a bottom 15 plate 86, a plate 87 spaced upwardly therefrom, and a cylindrical support member 88 supporting the plate 87 on the bottom plate 86. The bottom plate 86 is circular and is adapted to rest on an annular bearing member 89 and is guided 20 within a circular guide 90 formed integral with the main frame 10 and extending upwardly therefrom. An annular bearing member 91 is adapted to rest on the top portion of the bottom plate 86 and its upper surface is engaged 25 by a suitable annular ring 92 forming a guide means for the bottom plate 86 so said plate and the discharge conveyor 12 may be rotated about a vertical axis for discharging material at various angles with respect to the conveyor 14. 30

The discharge conveyor 12 is of the wire mesh belt type and a suitable wire mesh belt 93 is driven from a motor 94 on the underside thereof by means of a suitable chain and sprocket drive in an ordinary manner and generally indicated by reference character 95.

With reference to Figure 7 and a preferred form of the use and operation of the device of my invention, the loading machine is shown in solid as being disposed adjacent one side of a 40 mined coal face with its gathering arms 25 being fed into the mined coal. Both of the flexible feeding members 67 are connected to jacks 96. The rearward end of the discharge conveyor 12 is disposed over a suitable conveying mechanism 45 generally indicated by reference character 97. As power is applied to the feed drums 40, the gathering arms 25 being driven about the guide members 23, the flexible feeding members 67 feed the inclined loading element 11 into the 50 loose material. The loose material moved onto the conveyor 14 by the gathering arms 25 is discharged into the discharge conveyor 12 from where it is discharged into the conveying mechanism 97. 55

As the loading machine progresses into the coal, the conveying mechanism 97 is moved therewith. As the conveying mechanism is moved with the loading machine, said loading machine is simultaneously turned by manipulating either or both of the feed drums 40 until said machine is positioned so it may be moved substantially parallel with the coal face, the jacks 96 being moved as the loading operation 60 progresses. The loading mechanism being so positioned, is moved along the face of the coal so as to continuously load and discharge the mined coal into the conveying mechanism 97, which conveying mechanism in turn loads said 65 loose material onto suitable material carrying means, such as mine cars or other conveyors, for transportation from the mine. The conveying mechanism 97 is then positioned as is indicated by broken lines, parallel with the face of the 70 75

coal and disposed a distance from the mined coal so that the discharge conveyor 12 may discharge material therein when disposed at right angles to the skid 10.

5 It may now be seen that a new and improved device has been provided for loading coal in mines which is constructed with a view towards utmost simplicity and compactness especially with regard to vertical dimensions, said machine being so arranged as to eliminate all support wheels or traction drive means which necessarily add to the height of the machine. It may also be seen that said loading device is of a relatively simple construction and may readily be 10 continuously fed into the material and is particularly adapted for loading into conveyors or other continuous material transporting mechanisms.

While I have herein shown and described one 20 form of my invention, it will be understood that the construction and arrangement of the various parts may be altered without departing from the spirit and scope thereof. Furthermore, I do not wish to be construed as limiting myself 25 to the specific form illustrated, excepting as it may be specifically limited in the appended claims.

I claim as my invention:

1. In a loading machine, a main frame, and 30 gathering and loading mechanism therefor comprising an inclined conveyer, an inclined apron disposed forwardly of and on each side of said inclined conveyer, a plurality of orbitally guided endless chains having gathering arms thereon guided in guide means mounted on said apron on each side of said inclined conveyor and extending forwardly of said conveyer, and individual drive means for each of said endless chains for driving said endless chains independently or simultaneously of each other comprising a 35 separate motor disposed beneath each of said endless chains and having a drive connection therewith.

2. In a loading machine, a main frame, and 45 gathering and loading mechanism therefor comprising an inclined conveyer, an inclined apron disposed forwardly of and on each side of said inclined conveyer, a plurality of orbitally guided endless chains having gathering arms thereon guided in guide means mounted on said apron on each side of said inclined conveyor and extending forwardly of said conveyer, and individual drive means for each of said endless chains independently or simultaneously of each other comprising a 50 separate motor disposed beneath each of said endless chains and having a reduced geared drive connection therewith.

3. In a loading machine, a main frame, and 60 gathering and loading mechanism therefor comprising an inclined conveyer, an inclined apron disposed forwardly of and on each side of said inclined conveyer, a plurality of orbitally guided endless chains having gathering arms thereon guided in guide means mounted on said apron on each side of said inclined conveyor and extending forwardly of said conveyer, and individual drive means for each of said endless chains independently or simultaneously of each other comprising a 65 separate motor disposed beneath each of said endless chains on the underside of said apron, said motors having their axes extending generally longitudinally of said apron and having a drive connection with said endless chains.

4. In a loading machine, a main frame, and gathering and loading mechanism thereof comprising an inclined conveyer, an inclined apron disposed forwardly of and on each side of said inclined conveyer, a plurality of orbitally guided 5 endless chains having gathering arms thereon guided in guide means mounted on said apron on each side of said inclined conveyer and extending forwardly of said conveyer, and individual drive means for each of said endless chains for driving said endless chains independently or simultaneously of each other comprising a separate motor disposed beneath each of said endless chains on the underside of said apron, said motors having their axes extending generally longitudinally of said apron, and a drive connection from each of said motors to said associated endless chains including a bevel gear and pinion and a plurality of reduction gears.

5. In a loading machine, a main frame adapted 20 to rest on and slide along the mine bottom, a conveyor extending from a point disposed forwardly of said main frame upwardly and horizontally to a point adjacent the rearward end of said main frame, an apron disposed to each 25 side of and extending forwardly of said conveyor, a pair of orbitally guided endless chains having gathering arms thereon guided on said apron and extending forwardly of said apron, and a motor on said main frame beneath said 30 conveyor and apron and having a motor shaft extending longitudinally thereof, a pair of feed drums having flexible feed members thereon, disposed beneath said conveyor and adapted to form a means for moving said main frame along 35 the ground, a selective drive connection from said motor to said feed drums comprising a worm in alignment with and driven by the forward end of said motor shaft, a worm gear driven thereby and a separate planetary geared 40 connection between said worm and each of said drums, and another drive connection to said conveyor comprising a worm in alignment with and driven from said motor shaft and a worm gear driven thereby.

6. In a loading machine, a main frame comprising a skid adapted to rest on and slide along the mine bottom, and gathering and loading mechanism therefor comprising an inclined conveyor, an inclined apron disposed forwardly of 50 and on each side of said inclined conveyor, a plurality of orbitally guided endless chains having gathering arms thereon, said orbitally guided endless chains being guided in guide means mounted on said apron on each side of said inclined conveyor and extending forwardly of said apron, and individual drive means for each of said endless chains for driving said endless chains independently or simultaneously of each other comprising a 55 separate motor disposed beneath each of said endless chains and having a drive connection therewith.

7. In a loading machine, a main frame comprising a skid adapted to rest on and slide along the mine bottom, and gathering and loading 65 mechanism therefor comprising an inclined conveyor, an inclined apron disposed forwardly of and on each side of said inclined conveyor, a plurality of orbitally guided endless chains having gathering arms thereon, said orbitally 70 guided endless chains being guided in guide means mounted on said apron on each side of said inclined conveyor and extending forwardly of said apron, and individual drive means for each of said endless chains for driving said end- 75

less chains independently or simultaneously of each other comprising a separate motor disposed beneath each of said endless chains and having a reduced geared drive connection therewith.

5. 8. In a loading machine, a main frame comprising a skid adapted to rest on and slide along the mine bottom, and gathering and loading mechanism therefor comprising an inclined conveyor, an inclined apron disposed forwardly of 10 and on each side of said inclined conveyor, a plurality of orbitally guided endless chains having gathering arms thereon, said orbitally guided endless chains being guided in guide means mounted on said apron on each side of said 15 inclined conveyor and extending forwardly of said apron, and individual drive means for each of said endless chains for driving said endless chains independently or simultaneously of each other comprising a separate motor disposed beneath each of said endless chains on the under- 20 side of said apron and having their axes extending generally longitudinally of said apron.

9. In a loading machine, a main frame comprising a skid adapted to rest on and slide along the mine bottom, and gathering and loading mechanism therefor comprising an inclined conveyor, an inclined apron disposed forwardly of 5 and on each side of said inclined conveyor, a plurality of orbitally guided endless chains having gathering arms thereon, said orbitally guided endless chains being guided in guide means mounted on said apron on each side of said 10 inclined conveyor and extending forwardly of said apron, and individual drive means for each of said endless chains for driving said endless chains independently or simultaneously of each other comprising a separate motor disposed beneath each of said endless chains on the under- 15 side of said apron and having their axes extending generally longitudinally of said apron and a bevel gear and pinion and a plurality of reduction gears connected between each of said motors 20 and its respective endless chain.

JOHN S. HOUSMAN.
